(57) CLAIM

I claim the ornamental design for a children's snow boot, as shown and described.

DESCRIPTION

FIG. 1 is a perspective view of a children's snow boot showing the claimed design;

FIG. 2 is another perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof;

FIG. 8 is a bottom view thereof; and,

FIG. 9 is an enlarged view of area 9 shown in FIG. 2.

The even dashed broken lines depict portions of the children's snow boot that form no part of the claimed design. The dash dot lines in FIGS. 2 and 9 are for the purpose of illustrating the enlarged view indicators and form no part of the claimed design.
